UNITED STATES PATENT OFFICE.

PETER J. MACK, OF ROCHESTER, NEW YORK.

WINDOW VENTILATOR.

Application filed March 17, 1921. Serial No. 452,960.

To all whom it may concern:

Be it known that I, PETER J. MACK, citizen of the United States, residing at Rochester, in the county of Monroe and 5 State of New York, have invented certain new and useful Improvements in Window Ventilators, of which the following is a specification.

This invention relates to a window ventilator and has as one of its principal objects to provide a device of this character which may be readily secured in a window casing beneath the lower sash of the window.

The invention has as a further object to 15 provide a ventilator so constructed that the lower sash of the window may, without removing the device from the window casing, be closed down.

And the invention has as a still further 20 object to provide a device which may be readily adjusted to meet the requirements of windows of different widths.

Other and incidental objects will appear hereinafter.

25 In the drawings:

Figure 1 is a fragmentary perspective view showing the outer side of a window of conventional design and illustrating my improved device in connection therewith,

30 Figure 2 is a perspective view showing the device in detail, the parts being disassembled, and

Figure 3 is a transverse sectional view on the line 3—3 of Figure 2, looking in the 35 direction of the arrows.

In carrying the invention into effect, I employ a preferably trough shaped body 10 which may be formed of suitable resilient sheet metal and, as particularly shown in 40 Figure 2, the longitudinal margins of the body are bent laterally in opposite directions to provide side flanges 11. Arranged in the ends of the body are screens 12 appropriately secured to the body and, as 45 will be observed, cross strips 13 are disposed to extend between the sides of the body at its ends for bracing said sides with respect to each other and sustaining the screens at their adjacent vertical margins, the screens 50 being also secured to said cross strips. As shown in detail in Figure 3, the cross strips lie flush with the outer faces of the flanges.

Normally coacting with the body 10 are 55 companion end plates 14. These end plates are also preferably formed of suitable resilient sheet metal and at their upper and lower

edges are bent to provide reentrant flanges 15 slidably embracing the flanges 11 of the body. The end plates may thus be adjusted upon the body for varying the length of 60 the device to meet the requirements of windows of different widths. At their outer end portions, the plates are bent laterally to define flanges 16.

In order that the mounting and operation 65 of my improved ventilator may be accurately understood, I have, in Figure 1 of the drawings, shown the device in connection with a window of conventional design, this view showing the outer side of the window. 70 The window sill is indicated at 17, the sides of the window casing at 18, and the lower sash of the window at 19. In practice, the body 10 is rested upon the window sill 17 and the end plates are adjusted outwardly 75 until the flanges 16 thereof abut the sides 18 of the window casing. Screws or other suitable fastening devices are then engaged through these flanges for securing the device in position, it being observed that the 80 body is arranged to project inwardly at the inner side of the window sash. Further, it is to be noted in this connection that the device is mounted immediately at the inner side of the plane of the sash so that the 85 outer sides of the end plates 14 lie substantially flush with the inner side of the bottom rail of the sash. By this arrangement the sash may, without removing the device from the window casing, be closed down. On the 90 other hand, by raising the sash as suggested, the ventilator will be exposed at its outer side while closely confronting the lower rail of the sash to form a substantially 95 closed joint therebetween. When the sash is raised, air may, of course, flow into the body 10 and through the screens 12 at the ends of the same into the room, the space between the inner ends of the end plates 14 providing an inlet opening for the ventilator. Accordingly, by adjusting the elevation of the sash, the size of said opening 100 may be varied to regulate the volume of air admitted through the ventilator. I accordingly provide an effective device for the purpose set forth and a device which may be readily employed in connection with any ordinary window.

Having thus described the invention, what is claimed as new is:

110 A window ventilator comprising a central body consisting of a vertically bowed plate

having vertically disposed flanges along its upper and lower edges, bracing strips secured across the open side of the body at the ends thereof flush with the flanges along the upper and lower edges thereof, foraminous members secured to the said strips and the end edges of the body, and end plates having reentrant flanges on their upper and

lower edges slidably engaging the flanges on the central body, said end plates being provided with laterally extending flanges at their outer ends adapted to be secured to a window frame. 10

In testimony whereof I affix my signature.

PETER J. MACK. [L.S.]
